ATTORNEY

UNITED STATES PATENT OFFICE

WILLIAM F. DEUTSCHER, OF NEW YORK, N. Y.

AEROPLANE CONSTRUCTION

Application filed March 25, 1931. Serial No. 525,177.

This invention relates to improvements in aeroplane construction and the invention contemplates certain improvements over the disclosure of my pending application, Serial 5 No. 467,669, filed July 14th, 1930.

One of the objects of the invention is to provide new and improved means whereby the efficiency of the atmospheric pressure produced by the forward movement of the plane 10 may be more effectively utilized in the lifting of the plane and the holding of it aloft.

Another object of the invention is to provide new and improved means whereby a greater degree of sub-atmospheric pressure 15 may be produced by the forward movement of the plane through the atmosphere thereby giving a greater lifting force per given unit of wing area.

Another object of the invention is to provide a new and improved wing for aeroplanes whereby the sub-atmospheric pressure utilized in maintaining the plane aloft is effectively assisted by utilization of the air currents passing beneath the wing of the plane. 20

A further object of the invention is to provide a new and improved arrangement of the propeller relative to the wing of the plane whereby the air currents produced by the revolution of the propeller will be utilized to 25 such an extent that the plane will be caused to rise from the ground without the necessity of having to make a run.

Other objects of the invention will be in part obvious and in part pointed out herein-after. 30

The invention accordingly consists in the features of construction, combinations of elements and arrangement of parts which will be exemplified in the construction hereinafter set forth, and the scope of the application of which will be indicated in the following claims. 40

In the accompanying drawing, wherein I have illustrated a preferred form of embodiment of my invention, 45

Figure 1 is a view in perspective of my improved aeroplane,

Figure 2 is a front elevational view thereof, 50

Figure 3 is a view in forward section

taken on the line 3—3 of Figure 2, looking in the direction of the arrows, and

Figure 4 is a fragmentary plan view of the upper surface of the wing.

Referring now to the drawing wherein similar reference characters refer to similar parts throughout the several views thereof, the reference numeral 1 denotes the fuselage of the plane which may be of conventional form. 55

Numeral 2 indicates the motor, and numerals 3 and 4 denote the usual vertical and horizontal rudders provided in aeroplane construction. 60

The reference numerals 5 and 6 denote the wings of the plane which are secured in any approved manner to the fuselage 1. 65

Referring now to the wing construction which is illustrated best in Figures 3 and 4, I provide a plurality of inclined vanes 7, 70 which are spaced apart and suitably connected to the upper and lower walls of the wings. These vanes are inclined rearwardly from the bottom wall to the top wall of the plane providing a plurality of spaces 8 75 between the vanes.

Extending from the top or upper edge 9 of each vane is a partition 10 which extends downwardly and forwardly and joins with the lower end or edge 11 of the neighboring vane as is clearly shown in Figure 3 of the drawing. These partitions extend lengthwise to each wing and form a barrier preventing air from passing through the wing from the lower surface to the upper surface thereof. They are preferably formed of an elastic material such as rubber, although in some instances they may be made of a relatively stiff and non-elastic material. 85

The forward edge of the wings, it will be noted, is relatively sharp, said edge being formed by a wall 12, which extends downwardly and forwardly from the upper edge 13 of the wing joining a forward extension 14 of the wing at a relatively sharp angle. This forward edge of the wing is preferably formed with longitudinally extending apertures 15 and 16, the purpose of which is to permit the air currents passing rearwardly by the plane to form a sub-atmospheric pressure. 90

sure in the compartment 17, formed in the forward edge of the wing.

Leading from the compartment 17 and extending rearwardly through all of the vanes 5 7 and partitions 10, is a conduit 18, which is open at both ends and is also open to the V shaped spaces 19 formed between each partition and its neighboring vain. This pipe 18 at its rear end is provided with trap 20 10 which prevents air from being sucked forwardly through the pipe by means of the sub-atmospheric pressure produced in the compartment 17 or in the V shaped spaces 19 of the wing of the plane. This trap 20 15 will at all times contain water.

If desired, side wings 21 and 22 may be provided upon the side walls of the fuselage as shown in my aforementioned co-pending application and these wings may also be constructed in a manner similar to the construction 20 of the wing I have above described.

Having thus described the construction of this embodiment of my invention, it will accordingly be seen that I have provided 25 means whereby lifting effect of the air through which the wings of the aeroplane are forced by the motor may be more effectively utilized, having provided on the top of the wing a plurality of independent chambers 30 which at all times will contain a sub-atmospheric pressure when the plane is in motion.

I have also provided means whereby the 35 effect of the air currents through which the plane is being forced by the motor and passing underneath the wing of the plane entering the inverted V shaped pockets 23 formed by the partitions 10 and their wings will be more effectively utilized in lifting the plane. 40 In other words, I have provided for a higher degree of vacuum on the top surface of the plane than it has heretofore been possible to obtain, and I also provide pockets on the under-surface of the plane whereby the air 45 under pressure is maintained exerting an upward and forward stress on the wings of the plane.

It will also be noted that the relation of 50 the propeller and the wing is such that the air currents produced by the propeller will have the effect of quickly lifting the plane from the ground.

The pipe or conduit which extends transversely of the wing and to the rear end of 55 the fuselage is utilized to conduct water from the compartment 14 of the wing and from the V shaped pockets formed upon the upper surface of the wing. The trap being filled with water effectively prevents air from 60 passing forwardly through this pipe, which air might interfere with the degree of sub-atmospheric pressure produced in the V shaped pockets formed in the upper wall and in the front compartment thereof.

65 As many changes could be made in the

above construction and many apparently widely different embodiments of this invention could be made without departing from the scope thereof, it is intended that all matter contained in the above description or shown in the accompanying drawing shall be interpreted as illustrative and not in a limiting sense. 70

It is also to be understood that the language used in the following claims is intended to cover all of the generic and specific features of the invention herein described, and all statements of the scope of the invention, which, as a matter of language might be said to fall therebetween. 75

Having thus described my invention, what I claim as new and desire to secure by Letters Patent is:

1. In aeroplane construction, a wing having a plurality of air tight pockets upon its upper and lower surfaces, and an elastic partition wall separating said pockets. 85

2. In aeroplane construction, a wing having in its upper surface a plurality of air tight pockets and in its forward edge a compartment open to the atmosphere, and means for discharging water from said compartment and from said pockets. 90

3. In aeroplane construction, a wing having a plurality of downwardly and forwardly extending rigid partitions whereby said wing is divided into a plurality of spaced compartments, and an elastic sheet extending from the upper edge of each partition to the lower edge of the partition located forwardly thereof. 95

4. In aeroplane construction, a wing having a plurality of vertically and rearwardly disposed vanes, said vanes being rigid and spaced apart, and an elastic partition wall joining the upper edge of each vane to the lower edge of the adjacent vane. 100

5. In aeroplane construction, a wing having a plurality of vertically and rearwardly disposed vanes, said vanes being rigid and spaced apart, means running transverse of said vanes to which said vanes are anchored, and an elastic partition wall joining the upper edge of each vane to the lower edge of the adjacent vane. 110

6. In aeroplane construction, a wing having a plurality of vertically and rearwardly disposed vanes, said vanes being rigid and spaced apart and inclined rearwardly from the lower surface to the upper surface of the wing, and an elastic partition wall joining the upper edge of each vane to the lower edge of the adjacent vane forwardly disposed thereto. 120

7. In aeroplane construction, a wing having a plurality of vertically and rearwardly disposed vanes, said vanes being spaced apart and inclined rearwardly from the lower surface to the upper surface of the wing, and an elastic partition wall joining the upper 125

edge of each vane to the lower edge of the adjacent vane forwardly disposed thereto.

8. In aeroplane construction, a wing having a plurality of pockets upon its upper surface, said pockets being formed by a plurality of vertically and rearwardly disposed rigid vanes spaced apart and having an elastic partition wall connecting the upper edge of each vane to the lower edge of the vane forwardly adjacent thereto.

9. In aeroplane construction, a wing having a plurality of pockets upon its lower surface, said pockets being formed by a plurality of vertically and rearwardly disposed rigid vanes spaced apart and having an elastic partition wall connecting the upper edge of each vane to the lower edge of the vane forwardly adjacent thereto.

10. In aeroplane construction, a wing having a plurality of pockets upon both its upper and lower surfaces, said pockets being formed by a plurality of vertically and rearwardly disposed rigid vanes spaced apart and having an elastic partition wall connecting the upper edge of each vane to the lower edge of the vane forwardly adjacent thereto separating said pockets.

In testimony whereof, I affix hereunto my signature.

30 W. F. DEUTSCHER.
